UNITED STATES PATENT OFFICE.

FRANCIS MOYSE, OF PARIS, FRANCE, ASSIGNOR TO CHARLES HENRI CLAUDEL, OF LEVALLOIS-PERRET, FRANCE.

CARBURETER.

1,197,227.

Specification of Letters Patent. Patented Sept. 5, 1916.

Application filed February 26, 1913. Serial No. 750,865.

To all whom it may concern:

Be it known that I, FRANCIS MOYSE, a citizen of the Republic of France, residing at 57bis Rue Emeriau, Paris, France, have 5 invented certain new and useful Improvements in Carbureters for Explosive Engines, of which the following is a specification.

This invention relates to carbureters, particularly those for use with internal combustion engines; and its principal object is to provide means for accurately regulating and controlling both the quantity and quality of combustible mixture supplied to such an engine.

According to the present invention, a fuel jet nozzle is disposed axially within an air conduit controlled by an oscillatable valve member having a passage into which said jet nozzle projects. The openings or ports 20 at the ends of said passage are arranged to be simultaneously variable in size as requirements demand, to govern the flow of air through the passage; and the valve parts are so arranged that for all sizes of such 25 openings or ports, a line connecting their centers is always substantially coincident with the axis of said conduit, and hence, also, with that of said jet nozzle. Moreover, the particular construction of the jet nozzle, 30 more fully hereinafter to be disclosed, is such as to give, especially when in combination with the general arrangement of parts above described, certain new and hitherto unattainable results in accurate control of the 35 carbureting operation.

For the purpose of affording a clear understanding of the principles of the invention, I have illustrated a particularly advantageous embodiment thereof in the accompanying drawings.

In the drawings, Figure 1 is a front elevation of a carbureter constructed in accordance with the invention, showing the device for operating the plug. Fig. 2 is a plan view of the carbureter partly sectioned on line A—A (Fig. 1), the double plug not being sectioned. Fig. 3 is a section on line B—B (Fig. 2) showing the arrangement of the double plug and of the nozzle. Fig. 4 45 is a section of the nozzle on a larger scale.

Inside of the valve body or conduit 1 oscillates a sleeve or hollow outer plug 2 provided with two ports 'a, b corresponding respectively to the opening 'a' for the suction 50 of air and to the opening 'b' for the outlet

of the combustible gaseous mixture from the valve body. Within this hollow outer plug is revolvably disposed another plug which is of the usual type *i. e.* provided only with a port *c*. The two plugs can be made 60 to move one within the other in contrary directions simultaneously by means of the operating device shown in Fig. 1. Upon the journals 4, 5 of the oscillating plugs are fixedly mounted levers 6, 7 connected by 65 means of links 8, 9, at point 10, with a lever which may be oscillated around a fixed point 11 by means of an operating handle. Fig. 1 shows two different positions of the device, one in full lines, the other in dotted lines. 70

It will be readily understood that one single motion of the operating handle will result

in two contrary rotating motions of the plugs 2, 3 by means of the links 8, 9 and of the levers 6, 7.

The ports *a, b, c* provided in the plugs 2, 3 may be of any suitable forms. As a matter of course the edges of the bottom opening *c* and of the corresponding port *a* are so contoured that after completion of the 80 closing motion, a sufficient free area is left for the passage of the nozzle 12 which delivers combustible fluid into the carbureting chamber. In the drawing the openings *a, b, c* are shown as being of oval form (Fig. 2) so as 85 to leave after completion of the closing motion of the plug the necessary opening for the passage of the nozzle at the bottom and to close completely the valve at the top or to leave a small passage for the gaseous mixture. The nozzle 12 is shown as lying substantially in the axis of the valve body and is therefore parallel to the course of air passing therethrough.

The nozzle 12 is in communication (Fig. 95 3) with the constant level fuel chamber 14 by means of a conduit 15 opening into the upper part of the receptacle 14 with the double purpose of heating the oil on its way to the carburation chamber and of preventing impurities from being drawn with the oil to the nozzle. The aforesaid heating is not absolutely necessary but may be attained by circulation of hot water or of exhaust gases at 30, 30.

Fig. 4 is a section of the nozzle on a larger scale. The vertical fuel supply tube 12 is provided near its top with a partition orificed as at 17, and the tube extends upwardly a short distance beyond this parti 110

tion in the form of a cylindrical part 12' which flares outwardly at its upper end to form a conical cup portion 13 provided with orifices 18, 18. Said conical portion 13 may 5 have depending therefrom an outer cylindrical wall spaced away from tube 12 and forming therewith an outer annular chamber 19. On the cone 13 is located a cover 20 provided in its center with the jet orifice 10 proper, said cover being maintained in position by means of an outer tube 22, whose upper edges may be bent inwardly to rest upon the cover, as shown. A smaller chamber or space A is thus formed immediately 15 above the portion 12' of the fuel supply tube, the purpose of which will presently appear. This tube 22 extends downwardly, forming a kind of envelop or skirt whose lower edge 23 is adjacent a constricted portion 20 of the passage through the valve body, that is, adjacent a locality where the air current has its greatest velocity. It will be seen that the envelop 22 serves to inclose a downward extension of annular space 19. It may 25 be noted that the fuel level L is somewhat higher than the orifice 17 in order to insure a fuel reserve for re-starting the engine.

The operation of the apparatus is clear from the foregoing description. Air is 30 aspirated through the hollow valve body by the engine to which the carbureter is attached, the course of the air currents being indicated by the full arrows. The air travels parallel to the nozzle both outside 35 of the sleeve or envelop 22 and also through the annular space 19; and the somewhat diminished pressure resulting from the air flow induces flow of liquid fuel from the jet nozzle, such fuel being vaporized by and 40 mixing with the air passing to the engine. In the absence of special preventive means, higher velocity of air currents would produce still lower pressures on the fuel in 12'; and hence at higher engine speeds greater 45 quantities of fuel would be induced to flow from the jet nozzle. But such a result is well known to be undesirable; since leaner combustible mixtures are ordinarily required at higher speeds. In the arrangement 50 herein disclosed, the fuel feed is automatically regulated by the flow of air in the following manner: At high speeds, the swiftly flowing current of air passing into the annular space 19 is checked to some extent by the walls of the conical cup at the 55 upper end of the space and a certain dynamic excess pressure is thereby created in the chamber which is communicated through orifices 18 to chamber A above the fuel in 60 12'. The oblique disposition of the channels 18 causes streams of air passing therethrough to baffle, and this may aid in producing a slight plenum in A, as well as in 65 securing a very intimate mixture of air and fuel. This excess pressure in chamber A

partly opposes passage of liquid through orifice 17 into chamber A; and as the pressure increases with the speed of the engine, the carbureting, which tends to be too great at high speeds, is automatically controlled and kept within proper limits. 70

The arrangement of concentric valve plugs designed to be turned in opposite directions, as described, constitutes an important feature of the invention in its best 75 embodiment, in that it insures the centers of the apertures which terminate the passage through the valve always remaining substantially in line with the nozzle axis, thereby favoring uniform performance of 80 the carbureter. Moreover, this arrangement permits very accurate regulation and adjustment of the velocity and amount of the air current passing inside and outside of the cylindrical mantle 22, and this, in 85 turn, affects the pressure in chamber A in the manner before described. The parallelogram device shown in Fig. 1 for operating the compound valve permits of varying the effective area of the valve passage 90 approximately in proportion to the movement of the operating handle, which affords accurate regulation for all intermediate engine speeds. 95

What I claim is:

1. In a carbureter, the combination, with a conduit, and a fuel supply tube arranged therein, of a nozzle fed by said supply tube and comprising a fuel cup having a cover provided with a discharge outlet opening 100 into said conduit, a sleeve extending rearwardly from said cup and surrounding but spaced away from said tube to form an annular space opening rearwardly into said conduit, and passages through the walls of 105 said cup whereby air traveling forwardly through said annular space may pass into the fuel cup and thence to the discharge outlet. 110

2. In a carbureter, the combination with a conduit and a fuel supply tube disposed therein and substantially parallel to the axis thereof, of a walled chamber having an outlet to said conduit and arranged to receive fuel from said tube, and a hollow 115 cylindrical member surrounding a part of the tube and forming therewith an annular space open at the rear end to said conduit and communicating at the other end with said chamber. 120

3. In a carbureter, the combination with a conduit and a fuel supply tube disposed therein and substantially parallel to the axis thereof, of a walled chamber having an outlet to said conduit and arranged to receive 125 fuel from said tube, and a hollow cylindrical member surrounding a part of the tube and forming therewith an annular space open at the rear end to said conduit and communicating at the other end with said chamber 130

- through angularly disposed passages converging into said chamber and arranged to deliver baffling jets therewithin.
4. In a carbureter, the combination with 5 a conduit and a fuel supply tube disposed therein and substantially parallel to the axis thereof, of a walled chamber having an outlet to said conduit and arranged to receive fuel from said tube, and a hollow 10 cylindrical member surrounding a part of the tube and forming therewith an annular space open at the rear end to said conduit and communicating at the other end with said chamber, the edge of said cylindrical 15 member at its open end being adjacent a constricted portion of said conduit.
5. In a carbureter, the combination, with 20 a conduit, of a valve member arranged to govern flow of fluid in the conduit, said valve member having a passage or channel extending therethrough, a fuel supply tube projecting into said passage and substantially parallel to the direction of fluid flow, of a walled chamber having an outlet to said 25 conduit and arranged to receive fuel from said tube, a cylindrical envelop surrounding the projecting portion of said supply tube and forming therewith an annular space communicating at its forward end 30 with said chamber and open to the conduit at the other end, and means for operating
- said valve member to vary the effective size of said passage.
6. In a carbureter, the combination, with 35 a conduit, of a pair of valve plugs having coöperating passages forming a channel of variable inlet and outlet governing flow through said conduit, a fuel supply tube entering the channel in said valve plugs and arranged substantially parallel to the direction of flow through the conduit, a pressure chamber at the end of said supply tube 40 within said channel, a sleeve or envelop surrounding said supply tube and forming therewith an annular chamber which communicates through suitable passages with said pressure chamber, said sleeve extending from a point adjacent said chamber rearwardly or against the direction of flow in the conduit to a point adjacent a constricted portion of the conduit and being open at this end, and means for operating 45 said valve plugs simultaneously to vary the inlet and outlet of said channel.
- In testimony whereof, I have hereunto 50 subscribed my name this eighteenth day of February, 1913.

FRANCIS MOYSE.
